UNITED STATES PATENT OFFICE.

JOHN MERRY, OF NEW YORK, N. Y., ASSIGNOR TO BIGELOW CARPET COMPANY, A CORPORATION OF MASSACHUSETTS.

DESIGN FOR A RUG.

44,794.

Specification for Design.

Patented Oct. 28, 1913.

Application filed September 20, 1913. Serial No. 790,959. Term of patent 7 years.

To all whom it may concern:

Be it known that I, JOHN MERRY, a subject of the King of Great Britain, residing in New York city, in the county of New York and State of New York, have invented a new, original, and ornamental Design for a Rug of Carpet Sizes, of which the following is a specification, reference being had to the accompanying drawing, forming part thereof.

The drawing illustrates one quarter of a rug showing my new design; the remaining three quarters become duplicates thereof when the one quarter shown in the drawing is reversed bi-symmetrically from the central axes, both horizontal and vertical.

I claim:

The ornamental design for a rug, as shown.
JOHN MERRY.
